UNITED STATES PATENT OFFICE.

GEORGE H. HYNDMAN, OF BUTTE, MONTANA.

VALVE.

1,081,833.

Specification of Letters Patent. Patented Dec. 16, 1913.

Application filed February 8, 1913. Serial No. 747,143.

To all whom it may concern:

Be it known that I, GEORGE H. HYNDMAN, a citizen of the United States, residing at Butte, in the county of Silverbow and State of Montana, have invented certain new and useful Improvements in Valves, of which the following is a specification, reference being had therein to the accompanying drawing.

This invention relates to valves and has special reference to the kind of valves that are used in combination with pneumatic tires.

An object of this invention is to provide a valve of the character described which is adapted to relieve the pressure upon the interior of the tire after the same has reached a predetermined point.

Another object of this invention is the production of a valve of the class described which may be easily disconnected from the valve stem, whereby the several parts may be removed when it is desired to clean the same provided any particles of dirt or dust are carried by any of the several parts.

With these and other objects in view, this invention consists of certain novel constructions, combinations and arrangements of parts, as will be hereinafter fully described and claimed.

In the accompanying drawing: Figure 1 is a vertical section of a portion of the wheel showing the valve member attached thereto. Fig. 2 is a central vertical section of the valve member. Fig. 3 is a section taken on the line 3—3 of Fig. 2 looking in the direction of the arrow. Fig. 4 is a section taken on the line 4—4 of Fig. 2 looking in the direction of the arrow. Fig. 5 is an enlarged sectional view of a portion of the device showing the same as it discharges the excess pressure of air.

By referring to the accompanying drawing by numerals, it will be seen that the device is used in combination with a pneumatic tire 1 which is carried by the rim 2. The rim 2 is provided with the usual opening 3 through which the valve stem 4 is adapted to pass. This valve stem 4 is provided with an externally threaded portion 5 upon which the body 6 is threaded by means of the squared portions 7 which are adapted to be engaged by a wrench or other suitable means. Adjacent these squared portions 7 there is provided a threaded portion 8 which is adapted to receive the hood 9 which is placed over the valve member. The body 6

is provided with a reduced portion extending beyond the threaded portion 3 as illustrated at 10. Within this reduced portion 10 there is provided a central bore 11 and with transversely extending openings 12 which extend into this central bore 11. In order to provide a passage between this central bore 11 and the valve stem 4 there is provided a central passage 13. For this purpose the outer portion of the reduced member 10 is provided with an enlarged internally threaded portion 14 in which the cap 15 is threaded and this cap 15 is provided with the longitudinally extending aperture 16 and with the threaded portion 17 whereby a pump of the ordinary construction may be attached thereto for forcing air into the tire.

There is provided within the bore 11 a 75 slidable plunger 18 which carries a sleeve 19 in which the spring 20 is adapted to fit, the other end of the spring 20 bearing upon the inner face of the cap 15. The inner end of this slidable plunger 18 is provided with the 80 slightly concave face 21 which carries the washer 22. Adjacent this inner end 21 there are provided a plurality of apertures 23 which extend into the inner portion of the plunger 18 and then extend outwardly so as 85 to communicate with the circumferential groove 24. There is also provided a secondary plunger 25 which is adapted to work within the passage 26 formed in the plunger 18 and the outer end of this plunger 25 carries a spring 27 for holding the same in its correct position. It will be seen that when the air contained within the tire 1 reaches a sufficient pressure, the same will so bear upon the inner portion of the plunger 18 as to drive 90 the same down and compress the spring 20. The air will then pass down through the apertures 23 and into the groove 24 and when this groove 24 registers with the transversely extending openings 12 the air may 95 escape until the pressure within the tire is lowered sufficiently to allow the force of the spring to close the valve.

By referring to Fig. 2 it will be seen that the outer portion of the face 21 will bear 100 upon the cup-shaped portion 28 formed within the body 6. By this construction considerable space is obtained for allowing the washer 22 to be raised from the face 21, whereby the tire can be easily inflated. In 110 this manner a double acting valve has been produced whereby the tire can be inflated

and which is also provided with means for discharging excess air when the pressure reaches a predetermined point.

Having thus described the invention, what is claimed as new, is:—

1. A device of the class described comprising a body portion, a bore formed within said body, a slidable plunger positioned within said bore, an opening formed in one end of said body constituting an air passage, a closure cap positioned within the other end of said body, spring means positioned within said bore and bearing at one end upon said plunger and at the other end 15 upon said cap, said plunger provided with a plurality of apertures extending thereinto, said plunger also provided with a circumferential groove, said apertures communicating with said groove, said body provided 20 with a plurality of transversely extending openings, said plunger adapted to be driven down by the force of air and in this manner compressing said spring for allowing said groove to communicate with said transversely extending openings whereby the air 25 may escape.

2. A device of the class described comprising a body, said body provided with a centrally arranged bore, a slidable plunger 30 positioned within said bore, an air passage formed in one end of said body, a closure cap carried by the opposite end of said body, said slidable plunger provided with a sleeve, said body provided with a plurality of 35 transversely extending openings, a spring carried within said bore and positioned within said sleeve, the opposite end of said spring bearing upon said closure cap whereby said slidable plunger will be held upon 40 said air passage, a secondary plunger carried by said slidable plunger, said sleeve forming a closure for said transversely extending openings, said slidable plunger provided with a plurality of apertures, said 45 plunger also provided with a circumferential groove, said apertures communicating with said groove whereby when the pressure of air reaches a predetermined point the slidable plunger will be driven back so as

to compress the spring whereby the circumferential groove will register with the transversely extending openings and in this manner allow the air to escape.

3. A valve comprising a body having a central bore, said body provided with transverse openings communicating with said bore, a slidable plunger positioned in said bore, a cap carried within the outer end of said body, said plunger having a concaved inner end, said body having a concaved face 60 at the inner end of said bore, a spring positioned in said bore and bearing at one end upon said cap and at the opposite end upon said plunger for holding said plunger normally at the inner end of said bore, whereby 65 said concave faces constitute a pocket, said plunger having a circumferential groove, said plunger provided with apertures communicating with said groove and the concaved face thereof, said plunger provided 70 with a passage, a secondary plunger slidably mounted within said passage, said secondary plunger provided with a head normally resting upon the concaved face of said slidable plunger, a spring for holding 75 said head upon said face, said groove adapted to register with said openings, whereby air can pass through said valve in either direction when sufficient pressure is brought to bear thereon.

4. A valve comprising a body having a longitudinal bore, said body provided with transverse openings, a slidable plunger positioned within said bore and adapted to close one end thereof, means for holding said 85 plunger in the end of said bore, said plunger provided with a plurality of apertures extending from the top thereof to the sides thereof, said plunger adapted to be forced back by excessive pressure so as to allow 90 said apertures to register with said openings for allowing the escaping of the air.

In testimony whereof I hereunto affix my signature in presence of two witnesses.

GEORGE H. HYNDMAN.
